This application is a continuation-in-part of our co-pending application Serial No. 187,267, filed April 13, 1962.

This invention relates to a process for the production of acetylene from hydrocarbons. More specifically, it relates to a process for the production of acetylene in which the hot acetylene-containing gases are cooled with hydrocarbon oil.

It is known to prepare acetylene by subjecting hydrocarbons to high temperatures, for example by means of an electric discharge, hot flame gases or the heat liberated by incomplete combustion of hydrocarbons with oxygen. After having been exposed to the high temperatures, the hydrocarbons must be cooled very rapidly, and this is effected in conventional manner by quenching the hot gases with a liquid.

In the prior art methods, hydrocarbons having from one to ten carbon atoms and oxygen or oxygen-containing gas are used as initial materials, the ratio of hydrocarbon to oxygen being about 1:1 by weight. The gases are preheated to about 150° to 700° C. prior to the reaction. In the reaction space, a maximum temperature of about 1,300° to 1,650° C. is set up by the reaction of these gases. The reaction period is about two to five thousandths of a second.

It is known to use liquids with a high boiling point, as for example mercury, for the cooling operation. It is also known to use water for quenching the gases. The use of mercury is dangerous because mercury, especially mercury vapor, is very injurious to health. The use of water has the disadvantage that the acetylene-containing gases are mixed with steam and the heat energy contained in the steam is usually lost because the steam cannot be utilized for performing work. In the conventional quenching of the acetylene-containing gases with water under pressure, high-pressure steam or a condensate having a temperature above 100° C. is formed, but working under pressure is very troublesome because complicated equipment is required for the purpose. It is also known that hydrocarbon oils cannot be used for quenching the hot gases because the hydrocarbon oils would be decomposed at the high temperatures involved. Moreover, it is known to quench the hot gases in two stages with mineral oils. During quenching in the first stage, the mineral oils are partly cracked. The gases, which have been slightly cooled in the first stage, are then further quenched with mineral oils in a second stage. This method has the disadvantage that the acetylene-containing gases are contaminated by the gases resulting from the cracking of the mineral oils.

We have found that the hot gases obtained in the production of acetylene can be quenched in a simple way by carrying out the quenching in a single stage with high-boiling hydrocarbon oils, advantageously with high-boiling aromatic hydrocarbon oils, the volumetric ratio of hydrocarbon oil to gas being at least 1:100, and separating the carbon-black containing hot hydrocarbon oil from the gas.

The volume of the hydrocarbon oil may be measured, for example, in cubic meters and the volume of the gas in cubic meters (S.T.P.).

2

In accordance with this invention, it is possible to quench the hot gas (whose temperature is about 1,500° C. or more) to about 200° C. within a short time. There is no appreciable cracking of the high-boiling aromatic hydrocarbon oils in this process, i.e., the composition of the gas is not changed by the quenching because no gaseous impurities, such as ethylene, are formed during the operation. By reason of the high temperatures involved, part of the high-boiling aromatic hydrocarbon oils is vaporized in chemically unchanged form and the gas contains small droplets of the hydrocarbon oils used for quenching, but these impurities can be separated from the gas in a simple way and are not comparable with the gases resulting from the cracking of hydrocarbons.

15 By "high-boiling hydrocarbon oils" we mean hydrocarbon oils, especially aromatic hydrocarbon oils, which have boiling points of about 150° to 400° C., for example polynuclear aromatic hydrocarbons. The oils should be free of paraffinic constituents, i.e., purely aromatic. An oil should therefore have a pour point of —23° C. A higher pour point, e.g., a pour point of about 0° C. would indicate that the oil contains paraffinic constituents in addition to the aromatics.

20 The volumetric ratio of hydrocarbon oil to gas should be at least 1:100, i.e., 1 or more parts by volume of high-boiling hydrocarbon oil is required for quenching 100 parts by volume of hot gas. By the volume of the gas we mean its volume at standard conditions (S.T.P.), i.e., the amount of gas is measured, for example, in cubic meters (S.T.P.). After quenching, the hydrocarbon oil contains the bulk of the carbon black originally present in the hot gas.

25 It is advantageous to remove the hydrocarbon oil vapor, entrained droplets of hydrocarbon oil and the residual carbon black from the quenched acetylene-containing gas by means of low-boiling hydrocarbon oil, preferably low-boiling aromatic hydrocarbon oil (specific gravity less than 0.95), by washing the gas and cooling it to the boiling point of the low-boiling hydrocarbon oil. This 30 process offers the advantage that the carbon black is completely removed from the gas without the use of mechanical means, such as filters. Another important advantage of the process is to be seen in the complete separation of the high-boiling hydrocarbon oil from the acetylene-containing gas because, upon condensation of the water vapor contained in the gas, any residues of this oil in the acetylene-containing gas will form a stable emulsion in the condensate, and such an emulsion renders the removal of oil and water very difficult. By removing the carbon black without the use of mechanical means, substantially ash-free carbon black is obtained which, after separation from the hydrocarbon oil, is a valuable by product. In the conventional separation of carbon black from acetylene-containing gases by means of water and coke filters, 35 the carbon black is contaminated by fines originating from the coke of the coke filter. Hence, the carbon black has a considerable ash content and cannot be used for conventional applications.

40 By "low-boiling point oils" we mean hydrocarbons, especially aromatic hydrocarbons, which have boiling points of about 80° to 200° C. and specific gravities of less than 0.95, especially specific gravities of from 0.87 to 0.94, for example 0.90.

45 The difference in the boiling points of any two oils used should be from 30° to 200° C., i.e., the boiling point of the high-boiling oil should be from 30° to 200° C. higher than that of the low-boiling oil. On no account must the difference be less than 30° C. The low-boiling oil may consist to the extent of 100 percent of paraffins. Provision should be made, however, that the two oils 50 cannot intermix in application, as otherwise cracking products are liable to be formed and these would pass

into and contaminate the acetylene-containing gas if the high-boiling oil is reused for quenching purposes.

Washing of the gas with the low-boiling hydrocarbon oil may be effected, for example, by introducing the acetylene-containing gas, at a temperature of about 180° C., into the bottom of a distilling and fractionating column, allowing it to ascend therein, and adding the liquid low-boiling hydrocarbon oil at about the middle of the column. The low-boiling hydrocarbon oil vaporizes upon coming into contact with the hot gas and abstracts the heat of vaporization from the gas. The high-boiling hydrocarbon oil is thereby condensed out and can be withdrawn at the bottom. The vapor of the low-boiling hydrocarbon oil rises in the column and is partly condensed at the top of the column. In this way, a reflux of low-boiling hydrocarbon oil is formed in the upper part of the column, while a reflux of high-boiling hydrocarbon oil is formed in the lower part thereof. By these refluxes, complete separation of the high-boiling hydrocarbon oil and almost complete removal of the carbon black from the acetylene-containing gas is accomplished. When the gases leaving the top of the column are subsequently cooled to below the dew-point of the water vapor contained in the gases, the vapors of the low-boiling hydrocarbon oil are condensed and a condensate is obtained in which water and hydrocarbon are present in two layers and can readily be separated from each other.

It is advantageous to collect the high-boiling hydrocarbon oils separated from the gas and to use their heat energy profitably for some purpose. The considerable amount of heat energy abstracted from the hot gas during quenching can thus be utilized for other purpose without the need to carry out the production of acetylene under pressure, as has to be done if the hot gases are quenched with water and the heat transferred to the water or water vapor is to be used profitably.

In the process according to this invention, the carbon black formed in the production of acetylene is taken up by the high-boiling hydrocarbon oil. If the heat energy contained in the hot oil is recovered as described above, it is advantageous to reuse the oil, from which the heat energy has been substantially abstracted in a heat exchanger, for quenching acetylene-containing gases, i.e., the high-boiling hydrocarbon oil is recycled. During each cycle, the oil takes up the carbon black contained in the quenched gas and thus becomes enriched in carbon black. It is advantageous to carry out this cyclic process in such a way that the carbon black content of the recycled high-boiling hydrocarbon oil is adjusted to a maximum of about 35% by weight by withdrawing an appropriate amount of carbon-black containing oil from the circulation and replacing it by oil which is free from carbon black or contains only a small amount of carbon black.

The carbon black containing oil removed from the circulation may, for example, be burnt and the carbon black thus utilized profitably in a simple way. The carbon black containing oil may obviously also be freed from carbon black by mechanical methods for example by means of filters or centrifuges, and then returned to the above-mentioned circulation.

The present invention will be further described with reference to the accompanying drawing in which FIGURE 1 is a flow-sheet showing the course of the process and FIGURE 2 diagrammatically illustrates an apparatus, by way of example, in which the process can be carried out.

Referring to FIGURE 1 oxygen O₂ and hydrocarbon CH are heated up in separate preheaters 1 and 2 and mixed thoroughly in a mixer 3. The homogeneous mixture is passed into a combustion chamber 5, where it is converted in a flame reaction into an acetylene-containing cracked gas, which is quenched with oil at 7. The cracked gas is then passed on to further purification and into the processing plant (not shown) while the oil is recycled to 7 via a heat exchanger 6 in which steam is pro-

duced. A small portion of the carbon black containing oil is withdrawn and used as fuel in preheaters 1 and 2. This amount of oil is replaced by fresh oil from a container 4.

Referring to FIGURE 2 gasoline and oxygen are fed into a burner 10 through line 8 and 9 respectively and reacted therein to acetylene. The hot gas is quenched with a high-boiling oil at 11 and thence passes into the washing column 12 where it is cooled with low-boiling oil fed in through line 13. The hot oil collects at 14 and from there flows back to 11 through cooler 15 to be reused as quenching oil. The gas passes through line 16 into a cooler 17 to be cooled with water fed in through line 18. The low-boiling oil collects at 19. It is stripped 15 of water and recycled to the washing column 12 through line 20. The water recycles through line 21 and cooler 22 into the cooler 17. The cooled moist acetylene-containing gas is discharged through line 23.

The invention will be further illustrated by, but is not limited to, the following examples.

Example 1

370 kg. per hour of gasoline and 250 cubic meters (S.T.P.) per hour of oxygen are heated separately to 360° C. in two preheaters. The two are mixed and converted in a burner into acetylene-containing gas. At the outlet of the burner the hot cracked gas is quenched with an aromatic hydrocarbon oil having a boiling point of 240° to 360° C., the oil being used at a rate of 40,000 kilograms per hour. The cracked gas, now at a temperature of 180° C., contains about 10% by volume of acetylene and less than 0.5 g. of carbon black per cubic meter (S.T.P.). At the same time, 650 kg. per hour of steam saturated at 150° C. is obtained in a heat exchanger by heat exchange with the oil.

Example 2

520 cubic meters (S.T.P.) per hour of methane and 300 cubic meters (S.T.P.) per hour of oxygen are heated separately to 600° C. in two preheaters. The two are mixed and converted in a combustion chamber into acetylene-containing gas. At the outlet of the combustion chamber, the hot cracked gas is quenched with a high-boiling aromatic hydrocarbon oil having a boiling point of 240° to 360° C., the oil being used at a rate of 40,000 kilograms per hour. The cracked gas, now at a temperature of 180° C., contains about 8% by volume of acetylene and about 0.3 g. of carbon black per cubic meter (S.T.P.). At the same time, 700 kg. per hour of steam saturated at 150° C. is obtained by heat exchange with the oil.

Example 3

In the manner described in Example 1 a gas with 10% of acetylene is produced from gasoline and oxygen at a rate of 800 cubic meters (S.T.P.) per hour. The gas which contains high boiling oil in vapor form is obtained with a temperature of 180° C. It is quenched with 2 cubic meters per hour of a low-boiling oil having a boiling point of 90° to 190° C., the temperature of the gas falling to 100° C. The oil used for quenching is mainly aromatic containing only a very small amount of paraffinic constituents. The vaporous high-boiling oil is condensed and the liquid high-boiling oil is reused for quenching. The gas is further cooled down from 100° to 30° C. by directly spraying it with water. The end product is a moist acetylene-containing gas having a temperature of 30° C. The amount of cooling water used is 20 cubic meters per hour. The low-boiling oil is condensed and reused for quenching the gas at 180° C.

What we claim is:

1. In a process for the production of acetylene by subjecting hydrocarbons to a high cracking temperature of about 1300° to 1650° C., quenching the resultant hot gas from said cracking temperature to a lower temperature and separating carbon black from said gas, the improve-

ment which comprises: initially quenching said hot gas in a single stage with a high-boiling quenching liquid consisting essentially of an aromatic hydrocarbon oil which has a boiling point above about 150° C. and which is stable against cracking at said high temperatures in a volumetric ratio of said oil to said gas of at least 1:100; and separating the carbon black containing hot oil from the gas.

2. A process as claimed in claim 1 wherein the quenched gas containing acetylene and a portion of said high-boiling aromatic hydrocarbon oil which has been vaporized during quenching is washed with a low-boiling hydrocarbon oil having a boiling point above about 80° C. and a specific gravity of less than 0.95 and cooled to the boiling point of said low-boiling hydrocarbon oil.

3. A process as claimed in claim 2 wherein a low-boiling aromatic hydrocarbon oil is used for said washing.

4. A process as claimed in claim 3 wherein water vapor contained in the acetylene-containing quenched gas

is condensed together with said low-boiling aromatic hydrocarbon oil after said washing, and the resulting two layers of water and oil separated from each other.

5. A process as claimed in claim 3 wherein said high-boiling aromatic hydrocarbon oil has a boiling point of about 150° to 400° C. and said low-boiling aromatic hydrocarbon oil has a boiling point of about 80° to 200° C., the difference in the boiling point of the two oils being at least 30° up to about 200° C.
